CLAIM

The ornamental design of a padding for a cervical collar, as shown and described.

DESCRIPTION

FIG. 1 is a top, front perspective view of a padding for a cervical collar, showing our new design;

FIG. 2 bottom, rear perspective view thereof;

FIG. 3 is top plan view thereof;

FIG. 4 is a left side elevation view thereof, the right side elevation view being a mirror image;

FIG. 5 is a bottom plan view thereof;

FIG. 6 is a rear elevation view thereof;

FIG. 7 is a front elevation view thereof;

FIG. 8 is a top, front perspective view of the padding for a cervical collar of FIG. 1, in condition of use for clarity of disclosure; and,

FIG. 9 is a top, rear perspective view thereof.

In the drawings, the broken lines in FIGS. 8 and 9 depict environmental subject matter and form no part of the claimed design.
